PUMPING APPARATUS

Jean Mercier, New York, N. Y.

Application April 1, 1942, Serial No. 437,123
In France April 3, 1941

5 Claims. (Cl. 103—75)

The present invention relates to apparatus for pumping liquids and more especially for deep pumping.

It is concerned with pumps of the type in which the column of liquid in the pump main is yieldingly supported and caused to perform oscillations. This type of pump is usually so arranged that the final phase of the upward movement of the column produces a suction effect whereby a supply of liquid is drawn—generally through a non-return valve—into the base portion of the pump main while a corresponding quantity of liquid is—directly or indirectly—discharged from the pump.

A primer mover, generally a piston-cylinder unit, supplies the required energy by imparting an impulse to the liquid column at the beginning of the downward movement and of such force that the energy accumulated in the yielding support at the end of the downward movement is sufficient to produce the desired upward movement.

I have found that the energy efficiency of pumps of that type depends to a great extent upon the correct timing of the impulses imparted to the liquid column by the primary mover. This applies, particularly, to machine actuated pumps.

It is an object of the present invention automatically to synchronize the action of the primary mover with the given period of oscillation of the liquid column so that the mover acts on the column during the downward movement without interfering with its rise.

To that end I provide pilot means controlled by the flow of fluid in the pumping apparatus which are adapted to govern the operation of the machine actuating the same. It is a feature of the present invention that the aforesaid pilot means afford effective synchronization even in case of variations of the period of oscillation of the liquid column.

According to a further feature of my present invention additional masses may be incorporated in the oscillating system to reduce the frequency of the oscillations. This feature is of advantage in connection with manually operated pumps whenever the given period of oscillation requires an inconvenient rhythm of power strokes. It may also be applied to machine operated pumps where it will afford a possibility to reduce the output of a given pump without materially affecting the energy efficiency.

Other features of the present invention will result from the following detailed description of three embodiments thereof, given by way of ex-

ample and illustrated in the accompanying drawings.

Fig. 1 is a diagrammatical section of an apparatus for pumping water from a well according to the present invention;

Fig. 2 is a partial diagrammatical section showing a modification of the embodiment of Fig. 1;

Fig. 3 is a diagrammatical section of an embodiment in which the energy is supplied by a hydraulic jack.

In Fig. 1 pipe 6 connects pump body 1 with the source of liquid to be pumped. The portion of pipe 6 adjacent to said source is enlarged to form a cylindrical casing 7. A member 8 slidably engaging said casing is urged upwardly by a spring 9. Member 8 carries, in its top portion, a non-return valve 10 which controls the admission of liquid into pipe 6.

A piston 2 slidably engaging pump body 1 is provided to impart impulses to the liquid column in pipe 6.

Piston 2 is actuated by an electric motor 4, driving, through a belt and a pulley, a toothed wheel 5 in mesh with a rack 11 rigid with the piston rod 3. Suitable means (not shown) cause wheel 5 to engage rack 11 when motor 4 is working and to disengage the same when the latter is stopped. The electric circuit 12 of the motor 4 includes a contact 13—14 for closing or interrupting this circuit. Contact 13 may be stationary, while contact 14 is carried by a lever 15 pivoted at 15A. This lever 15 is connected, at 15B and 15C, to the rods of two small pistons 16 and 17 slidable in cylindrical tubes connected through conduits 18 and 19 with the interior of pipe 6 containing the column of liquid. Conduit 18 opens into pipe 6 through a branch extending upwardly, while conduit 19 opens into the same pipe 6, but through a branch extending downwardly.

Pistons 16 and 17 float on the liquid in conduits 18 and 19 and prevent outflow of liquid from the same.

Contact 14 and lever 15 are so arranged that the former engages contact 13 whenever the level of the liquid in conduit 18 is above that of the liquid in conduit 19. In the opposite position, or when the level in both conduits is the same, both contacts will be at a distance from each other. A suspension device for the column of liquid is provided in the inferior end portion of pipe 6, which is essentially constituted by a spring 9 and a sliding member 8 carrying a check valve 10.

The operation of this pumping apparatus is as follows:

When piston 2 has completed a forward stroke spring 9 is fully compressed and movement of the liquid column momentarily ceases. Consequently, the liquid levels in conduits 18 and 19 become equal, contacts 13 and 14 are separated from each other and motor 4 is stopped.

When the column of liquid which oscillates in pipe 6 starts rising under the effect of the expansion of spring 9, it exerts pressure upon the liquid contained in conduit 19, which rises and lifts piston 17. Lever 15 pivots upwardly and moves contact 14 away from contact 13 whereby circuit 12 of motor 4 is kept interrupted. Piston 2 is pushed back into its extreme right hand position and liquid is discharged through the upper opening in pump body 1. The rise of the liquid column continues due to the inertia of the liquid body after spring 9 is fully expanded. During this final phase of the upward oscillation the pressure in the bottom portion of pipe 6 and in casing 7 drops below that of the liquid surrounding the same, slide valve 10 is lifted and liquid admitted. When the column of liquid starts moving downwardly check valve 10 is closed. The liquid present in conduit 18 rises, pushes piston 16 upwardly and lowers lever 15 so that contacts 14 and 13 meet. Circuit 12 is thus closed, motor 4 starts and pushes piston 2 toward the left. The movement of motor 4 is stopped by the outward displacement of piston 17.

In the embodiment of Fig. 2, the impulses intended to sustain the oscillations of the column of liquid are supplied by an electro-magnet 20-21. The circuit 12 of the coil of the electro-magnet includes, as in the preceding embodiment, a contact 13-14 controlled by a lever 15 subjected to the action of pistons 16 and 17.

The operation is analogous to that which has been above described. The closing of contacts 13-14 energizes the electro-magnet, whose core 20 is then pulled downwardly and acts directly upon piston rod 3. The upward movement of the column of liquid causes contact 13-14 to be interrupted, de-energizes the electro-magnet and allows piston 2 to move upwardly under the effect of the liquid thrust.

In the arrangement shown by Fig. 2, the liquid flowing out from the pump body 1 passes through a reservoir 22, containing at its upper part, at 23, a compressed air cushion, and acting as an accumulator, so that the liquid delivered by the pumping apparatus through pipe 24 may have a continuous flow. The period of oscillation of the column of liquid depends obviously from the length of this column which may lead, in some cases, to the necessity of movements at a rhythm which is inconvenient. In this case, according to a feature of the invention, I introduce into the oscillating system an additional mass which modifies the period of oscillation of the whole. This additional mass may be mounted in any portion of the oscillating system, that is to say either on the elastic suspension means or on the device for sustaining the oscillations of the whole, or again in the column of liquid itself.

In the embodiment of Fig. 2 electro-magnet 20 carries additional masses M to correct the period of oscillation of the liquid column.

In Fig. 3, the motor which supplies the desired impulses to the column of liquid is actuated by a fluid under pressure, including for instance a piston 25 rigidly connected to piston 2 and sliding in a cylinder 26 adapted to be connected alternately with an inlet opening 27 for fluid under pres-

sure and with an outlet opening 28 for the same, these openings being controlled by a slide valve 29.

This slide valve 29 is operated in response to the oscillations of the column of liquid in pipe 6 in the following manner:

Pipe 6 is connected to the pump body 1 through a chamber 30 communicating with pump body 1 through a passage 31 adapted to accommodate exactly a piston 32. This piston 32 is subjected to the elastic action of a spring 33, which tends to push it toward the right. It is carried by a rod 34 connected to a lever 35, pivoted at 36, which lever is, in turn, connected by a link 37 to slide valve 29.

The oscillations of the liquid column are possible by an arrangement of the lower portion of the pumping apparatus similar to that in the preceding embodiments.

During the principal phase of the upward movement of the liquid column piston 3 is in its extreme right hand position so as not to interfere with the communication between delivery pipe 6 and pump body 1. At the same time piston 32 projects beyond passage 31 into the interior of body 1. In this position of the piston 32 slide valve 29 obstructs inlet 27 while cylinder 26 is in communication with outlet 28. The beginning of the downward movement of the liquid column carries piston 32 into the position shown whereby slide valve 29 closes outlet 28 and opens inlet 27. Accordingly, fluid under pressure enters cylinder 26, driving pistons 25 and 2 to the left into the position shown. This amplifies the downward movement of the liquid column which forces sliding member 8 downward in casing 7 and compresses spring 9. When the column of liquid rises in pipe 6, piston 32, under the combined actions of this liquid end of spring 33, moves past passage 31 and penetrates into the pump body 1. Accordingly lever 35 and link 37 displace slide valve 29 into its right hand position so that cylinder 26 is connected with the outlet 28. Piston 2 then moves toward the right, without encountering any resistance.

The upward movement of the column continues after spring 9 is fully expanded and produces a suction effect. Accordingly, check valve 10 is raised and liquid to be pumped is drawn through member 8 into casing 7 and pipe 6.

This arrangement is primarily designed for cases where the fluid under pressure supplied to cylinder 41 is an elastic fluid, because, in this case, it is possible to admit fluid during only a small portion of the stroke and then to make use of its expansion.

I will now give, by way of example, numeric indications relative to the practical construction of an apparatus according to the present invention.

In this example, it will be assumed that it is desired to pump water from a well having a depth not exceeding 50 metres.

In this case, the total length of the pipe may vary from 60 to 30 metres.

If no additional masses such as those shown at M in Fig. 2, are used the period of oscillation of the system depends only upon the length of the pipe.

However, it should be noted that there are two periods to be considered for each depth, to wit:

(a) The natural period of the system when the apparatus is not supplying liquid, which will be hereinafter called non-working period, and,

(b) The period of the system when liquid is

being pumped, which will be hereinafter called working period, the latter being higher than the non-working period, because it is equal to the sum of the latter and of the time of flow of the liquid that is pumped.

For a pipe of a length of 60 ms., the pumping frequency corresponding to the state of resonance is 85 pump strokes per minute; for a length of the pipe of 30 ms., it is 120 pump strokes per minute.

Concerning the dimensions of the apparatus, the diameter of the upper portion of piston-like member 8, is 75 mms.; the stroke of this member is 87 mms.

Spring 9 is a coil spring having a diameter of 87 mms. It is made of a metal wire 12 mms. in diameter and wound into 15 revolutions. The height of spring 9 is 180 mms., when compressed, and 267 mms., when expanded.

The diameter of pipe 6 is 40 mms.

In these conditions, for a length of the pipe of 60 ms., the pumping frequency which corresponds to the resonance of the system is 79 strokes per minute. It corresponds for the dimensions above stated and an elevation of liquid of 50 ms., to a discharge of 875 litres per hour with a stroke of 30.6 cms. of the pump lever, the maximum velocity of water in the pipe being 1.80 m. per second.

With the same apparatus, but with a length of the pipe of only 30 ms. and an elevation of 25 ms., the rhythm of pumping is 100 strokes per minute, producing a discharge of 1460 litres per hour, which corresponds to a stroke of the lever of an amplitude of 20.3 cms., the maximum velocity of water in the pump being 1.90 m. per second.

The figures above stated are the theoretical results given by calculations. If account is taken of pressure drops in the pipe, the following results can be expected: For a pipe length of 60 ms., the efficiency will be 54%; for a pipe length of 30 ms., the efficiency will be 62%.

The efficiency increases when the output decreases.

Now, if the same apparatus is to be used for working between 30 ms. and 15 ms. of pipe length, while keeping the same range of frequencies, it suffices to ensure a supplementary pressure of 266 grs. per cm.² for a stroke of 20 cms. of the pump lever. In the case of an apparatus having the characteristics above indicated, this supplementary pressure being intended to overcome the pressure drops of the liquid in the pipe under these conditions, the maximum velocity of the liquid in the pipe is 91 cms. per second.

Finally, concerning the pressures, it has been found that, at the bottom of the water column, if the length of the pipe is 60 ms. and with an elevation of 50 ms., the maximum pressure is equal to 17.5 kgrs. per cm.². It is therefore possible practically to use weldless cold-drawn tubes of 40/49, as supplied on the market, which are tested for at least 20 kgrs. per cm.².

For a length of the pipe of 30 ms. and an elevation of 25 ms., the pressure at the bottom of the column of liquid is only 12 kgrs. per cm.².

While I have, in the above description, dis-

closed what I deem to be practical and efficient embodiments of the present invention, it should be well understood that I do not wish to be limited thereto, as there might be changes made in the arrangement, disposition and form of the parts, without departing from the principle of the present invention, as comprehended within the scope of the appended claims.

What I claim is:

10. 1. A pumping apparatus which comprises, in combination, a conduit adapted to contain a column of liquid, yielding suspension means for this column of liquid carried by the lower end of said conduit, whereby said column can oscillate in said conduit, motor means for imparting impulses to this column of liquid and pilot means responsive to the direction of flow of liquid through said conduit for controlling said motor so as to sustain the oscillation of liquid therein, a check valve at the lower end of said conduit for the inflow of liquid thereinto and discharge means at the top of said conduit.
15. 2. A pumping apparatus which comprises, in combination, a conduit adapted to contain a column of liquid, yielding suspension means for this column of liquid carried by the lower end of said conduit, whereby said column can oscillate in said conduit, electric motor means for imparting impulses to this column of liquid, a circuit for said electric motor means, a switch in said circuit, means operative by the flow of liquid through said conduit for operating said switch in such manner as to control said electric motor means, so as to sustain the oscillations of liquid therein, a check valve at the lower end of said conduit for the inflow of liquid thereinto and discharge means at the top of said conduit.
20. 3. A pumping apparatus according to claim 2, in which said means operative by the flow of liquid include two cylinders, pistons movable in said cylinders respectively and operatively connected with said switch so as to act thereon in opposite directions respectively and communication means interposed between said two last mentioned cylinders respectively and said conduit, said communication means opening in said conduit in directions opposed to each other.
25. 4. A pumping apparatus which comprises, in combination, a conduit adapted to contain a column of liquid, yielding suspension means for this column of liquid carried by the lower end of said conduit, whereby said column can oscillate in said conduit, a motor operated by a fluid under pressure for imparting impulses to this column of liquid, a slide valve for controlling said motor and a piston for operating said slide valve movable in a part of said conduit under the effect of the flow of liquid therein, for controlling said motor so as to sustain the oscillations of liquid therein, a check valve at the lower end of said conduit for the inflow of liquid thereinto and discharge means at the top of said conduit.
30. 5. A pumping apparatus according to claim 1 in which an adjustable mass is incorporated in the oscillating system to modify the period of oscillation thereof.

JEAN MERCIER.
